VETERINARY MOUTH SPECULUM

Albert A. Berzina, Whitman, Nebr.

Application October 7, 1936, Serial No. 104,525

2 Claims. (Cl. 128—14)

The present invention relates to new and useful improvements in veterinary mouth speculums, and has for its primary object to provide, in a manner as hereinafter set forth, a device of this character embodying a novel construction and arrangement through the medium of which the mouth of an animal, such as a horse, may be expeditiously opened and retained in open position without danger of injury to the operator.

Another very important object of the invention is to provide a veterinary mouth speculum of the aforementioned character which will permit the animal's mouth to be opened to any desired extent within a given range.

Other objects of the invention are to provide a veterinary mouth speculum which will be comparatively simple in construction, strong, durable, highly efficient and reliable in use, compact, light in weight and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation of the invention, showing the device in use.

Figure 2 is a perspective view, showing the device in closed position.

Figure 3 is a perspective view, showing the invention in open position.

Figure 4 is a detail view in perspective of the free end portion of the upper bars and the bit plate extending therebetween before the device is completed.

Figure 5 is a perspective view similar to Figure 4 but showing this portion of the device completed.

Figure 6 is a detail view in vertical section through one of the spring actuated pawls.

Figure 7 is a detail view in section, taken substantially on the line 7—7 of Figure 6.

Referring to the drawings in detail, it will be seen that the embodiment of the invention which has been illustrated comprises pairs of spaced upper and lower jaw bars 1 and 2, respectively, having oppositely curved rear end portions which are pivotally connected together, as at 3. The bars 1 and 2 are adapted to extend on opposite sides of the animal's head. Extending between the free forward end portions of the upper bars 1 and the lower bars 2 and preferably integral therewith are bit plates 4. As illustrated to advantage in Figures 4 and 5 of the drawings, the

bit plates 4, when the device is being made, project forwardly beyond the jaw bars 1 and 2 and these forwardly projecting portions are then formed to provide oppositely disposed rolls 5. It may be well to here state that the plates 4 and the rolls 5 thereon are adapted for engagement with the teeth of the animal.

Rigidly mounted on the upper and lower jaw bars 2 and spaced therefrom are guide bars 6 and 7, respectively. The bars 1 and 6 have formed 10 therein at longitudinally spaced points transversely aligned notches 8 the purpose of which will be presently set forth.

The reference numeral 9 designates a pair of hand operated levers which are pivotally mounted 15 at an intermediate point, as at 10, between the bars 2 and 7. The levers 9 are of substantially the curvature shown to advantage in Figure 3 of the drawings and said levers travel between the bars 1 and 6. Rollers 11 are journaled on the 20 levers 9 at an intermediate point for engagement beneath the bars 6 for forcing the device open after it is inserted in the animal's mouth. Pawls 12 are provided on the upper ends of the levers 9 for engagement in the notches 8 for releasably 25 securing the device in open position. Referring now to Figures 6 and 7 of the drawings, it will be seen that the pawls 12 are yieldingly urged into the notches 8 by coil springs 13 which are enclosed in said pawls.

The reference numeral 14 designates snap hooks which are loosely connected to the oppositely curved rear end portions of the jaw bars 1 and 2. The snap hooks 14 are mounted on a link 15 which, in turn, is mounted on a head 35 harness 16. The reference numeral 17 designates a nose strap which is connected at its ends to the rear portions of the bars 1 while the reference numeral 18 designates a chin strap or chain which is connected, at its ends, to the 40 forward end portions of the elements 2 and 7.

It is thought that the operation of the device will be readily apparent from a consideration of the foregoing. The invention is positioned in the animal's mouth where it is securely retained 45 by the head harness 16 and the elements 17 and 18. Then, by grasping the lower end portions of the levers 9 and pulling downwardly and forwardly thereon the pivotally connected upper and lower bars 1 and 2, respectively, will be forced 50 apart by the rollers 11 from the position shown in Figure 2 of the drawings to that illustrated in Figure 3 or, of course, until the desired position is reached. The construction and arrangement is such that the spring actuated pawls 12 will ride 55

past the notches 8 in one direction but said pawls will seat in said notches for releasably securing the levers 9 against movement in the opposite or forward direction. In this manner the device is 5 releasably locked in open position. To permit the device to be closed it is only necessary to lift the pawls 12 out of the notches 8 against the tension of the coil springs 13. It may be well to here state that the lower end portions of the levers 9 are formed to provide handles. The construction 10 and arrangement is also such that any pulling force exerted on the device by the head harness 16 will only tend to open said device wider.

It is believed that the many advantages of a 15 speculum constructed in accordance with the present invention will be readily understood, and although a preferred embodiment of the device is as illustrated and described, it is to be understood that changes in the details of construction 20 and in the combination and arrangement of parts may be resorted to which will fall within the scope of the invention as claimed.

What is claimed is:—

1. A speculum of the class described comprising 25 pairs of upper and lower jaw bars pivotally connected at one end portion, guides mounted on the upper jaw bars, said upper jaw bars having

longitudinally spaced notches therein, levers pivotally mounted on the lower jaw bars and adapted for swinging movement between the upper jaw bars and the guides, rollers journaled on said levers and engaged with the guides for forcing the 5 upper jaw bars away from the lower jaw bars, and spring actuated pawls mounted on one end of the levers and engageable in the notches for releasably locking the upper and lower jaw bars in open position.

2. A speculum of the class described comprising upper and lower jaw bars pivotally connected together at one end, bit plates extending between the other end portions of the upper and the lower jaw bars, oppositely disposed rolls on the forward ends of said bit plates engageable with the teeth of an animal, and means for spreading the upper and lower jaw bars, said means including levers pivotally mounted on the lower jaw bars, rollers journaled on said levers and operatively 15 connected to the upper jaw bars for forcing said upper jaw bars away from the lower jaw bars, and spring actuated pawls mounted on one end of the levers and operatively engageable with the upper 20 jaw bars for releasably securing the speculum in open position.

ALBERT A. BERZINA.
